DESIGN FOR AN AIRPLANE

Gilbert H. Altherr and Norman E. Nelson,
Dayton, Ohio

Application January 30, 1946, Serial No. 126,087

Term of patent 3½ years

(Cl. D71—1)

To all whom it may concern:

Be it known that we, Gilbert H. Altherr and Norman E. Nelson, citizens of the United States, both residing in Dayton, in the county of Montgomery and State of Ohio, have invented a new, original, and ornamental Design for an Airplane, of which the following is a specification, reference being had to the accompanying drawings, forming a part thereof, wherein:

Fig. 1 is a top plan view;

Fig. 2 is a front elevational view;

Fig. 3 is a side elevational view; and

Fig. 4 is a perspective view of an airplane, showing our new design.

We claim:

The ornamental design for an airplane, substantially as shown.

GILBERT H. ALTHERR.
NORMAN E. NELSON.
